SIGNAL MECHANISM

Clarence Edward Beach, Brookline, Mass.

Application April 16, 1936, Serial No. 74,706

Renewed August 3, 1938

8 Claims. (Cl. 177—361)

This invention relates to code signal formulating devices having so-called "perfect non-interference and succession" features, and more particularly to such devices as have facilities rendered effective during impairment of a normal signalling current path for formulating code signals in one or more abnormal or so-called "emergency" current paths.

Code signal formulating devices, such as those to which embodiments of this invention are particularly suited, are frequently employed in municipal and other fire alarm signaling systems, and, when so used, are many times referred to as "fire alarm boxes". In the interests of convenience and brevity of expression, the terms "signal formulating device", "signal box", "signal transmitter" or "fire alarm box" may be hereinafter more or less interchangeably employed.

Applicant's prior Patent No. 1,999,859, dated April 30, 1935, discloses a signal formulating device embodying features which have been found well suited to many of the practical situations where such devices are used, and the mechanism there specifically disclosed may be completely manufactured or produced by adaptation of, and addition of parts to, a widely used type of fire alarm box.

It seems probable, however, that formulating devices may be advantageously employed, under certain service conditions, notwithstanding that they fail to embody all of the functional features of a mechanism constructed in accordance with applicant's said prior patent; and it is believed that those purchasing such formulating devices will, in some instances, be influenced more by considerations of lower prices or fewer parts than by accomplishment of functions needful for minimizing, to a maximum extent, against losses of signals resultant from impairment of the normally effective signaling circuit.

Furthermore, there are many thousands of comparatively old style fire alarm boxes in service of the general type known as "Ideal". Some may consider it more expedient to alter such old style boxes so as to safeguard, to a considerable extent, against such alarm losses, rather than to replace these boxes by those of more modern type, even though the altered boxes may fail to fully avoid all preventable alarm losses.

It is therefore an object of this invention to provide code signal formulating devices which may be more economically manufactured and hence profitably sold at a lower price than devices constructed fully in accordance with the details of the disclosure of applicant's said prior pat-

ent, which improved devices may embody facilities for avoiding a substantial proportion of all preventable alarm losses.

It is a further and important object to provide such a device which may be produced by unchanged use of a substantial proportion of parts such as those heretofore employed in the "Ideal" type of fire alarm boxes, together with a minimum number of altered and added parts.

Other objects will be in part apparent and in part more specifically set forth in the ensuing specification.

In constructing this invention, the usual train or clockwork mechanism may be arranged to rotate a so-called "signal wheel" for effecting actuation of signal formulating contacts, which contacts are inter-related with a so-called "non-interference magnet" and with non-interference trap and succession effecting mechanism, all as or analogous to that accomplished in "Ideal" type fire alarm box mechanisms with which those skilled in this art are well acquainted.

The mechanism thus far referred to is so modified that the results heretofore obtained by movement of the non-interference armature out of the normal effective field of the non-interference magnet is, in accordance with the present invention, accomplished through a lesser movement of said armature, all of which movement is within the effective magnetic field. The mechanism is so altered that such limited retraction of this armature causes locking of the code signal formulating contacts (also hereinafter referred to as "key break mechanism") which locking action will be maintained, irrespective of subsequent movement of the armature in response to ensuing energizations of the magnet, until a stage is attained in the functional cycle of the mechanism which results in a renewed attempt to formulate the intended code signal in accordance with the teachings of the prior art.

It will be observed that the facilities just described embody a modification of those provided in prior or conventional forms of "Ideal" type boxes, in that not only do the non-interference armatures of such prior boxes move out of the normal effective range of the non-interference magnets in the event of interference, but no facilities are provided whereby such armatures may be brought or held within the range of effective magnet energization until conditions are right for testing to determine the propriety of again attempting signal formulation.

It is a further characteristic of such prior "Ideal" type boxes that if the non-interference

armature is at any time moved to attracted position during activity of the mechanism, whether by unintended manipulation or because of abnormally great magnet energization, the key break mechanism is thereby immediately rendered responsive to the code wheel and an incorrect signal formulation is likely to result.

In accordance with a more general aspect of this invention, facilities, including additional or supplemental key break mechanism operable responsive to the same or a different code wheel, is added to the structure of conventional "Ideal" type boxes (either as previously employed or as modified in accordance with the foregoing explanation). Such facilities render effective signal formulation between the normal and the emergency path (which may include the earth) only following deenergization of the non-interference magnet for a time longer than the longest period of deenergization of the normal current path incidental to formulation of any signal.

In accordance with certain of the specific forms of this invention, the contacts of such supplemental key break mechanism are continuously subject to functional actuation responsive to rotation of the code wheel; one of such contacts being connected to the normal current path and the other being subject to connection with the emergency conductor or ground through the action of switching mechanism which is caused to be actuated responsive to continued retraction of the non-interference armature for a certain prolonged period of time, as just explained.

In accordance with other specific embodiments of this invention, such supplemental key break mechanism normally is mechanically rendered unresponsive to the code wheel and its contacts are maintained in open circuit conditioning; said contacts being rendered responsive to rotation of the code wheel only when non-portative positioning of the non-interference armature has remained unaffected by energization of the non-interference magnet for a time, measured by the running of the train, and longer than the longest period of deenergization of the normal signaling current path incidental to the formulation of any signal.

For the purpose of facilitating comprehension of this invention, certain embodiments thereof are indicated in the accompanying drawings, in which

Figure 1 is an isometric view, generally diagrammatic for sake of clarity, indicating the application of an embodiment of this invention to a well known type of signal transmitter, various parts being shown relatively displaced much further than necessary in a physical embodiment;

Fig. 1A is a diagram of a part of the circuit arrangement of Fig. 1;

Figs. 2, 3, 4 and 5 show certain parts of the mechanism of Fig. 1 in various operative relationships; and

Figs. 6 to 11, inclusive, show various modifications of the mechanism and circuit arrangements indicated in Fig. 1.

The structure indicated in Fig. 1 embodies adaptations of and additions to parts of a fire alarm box such as that shown in Fig. 1 of a patent to J. W. Johnson, No. 621,093, dated March 14, 1899. Parts which may conveniently be constructed and operated the same as in said Johnson patent are herein given the identifying characters used therein, and reference may be had to that patent for further description of such

parts, as well as of the parts cooperating therewith which form no part of this invention.

The normal signal or code wheel E is fixed upon shaft 21 together with the gear C⁸ and the pinion 23, which gear and pinion form part of train-work such as that indicated by the aforesaid patent, and which train-work carries a detent flange A² in cooperative relationship with a tooth or projection B¹, associated with the detent arm B.

Said flange is cut-away at certain points so as to provide openings, such as the opening A³, for receiving the projection B¹ for purposes more fully described in the aforesaid Johnson patent.

The non-interference electromagnet C has the armature C³ associated in functional relationship therewith. This armature is carried by the armature lever C¹ which is pivotally mounted on the shaft C² and has the retractile spring C⁴ applied thereto. The tracer or so-called "key break lever" D² is arranged for cooperation with the toothed periphery of the code wheel E for functional actuation thereby; movement thus given to said lever being imparted to the code signal formulating contacts D through the insulating pin D³.

A moving part of the gear train, which may preferably be the flange A² (as indicated in the aforesaid patent) carries the pin A⁴ which engages the end A⁵ of the key break lever D² when the opening A³ is in or near alignment with the projection B¹, for purposes more fully described in the aforesaid Johnson patent.

A downwardly extending arm 41, associated with the armature lever C¹, carries, near the free end thereof, the bar 43; which bar, in turn, carries the pin 45. A finger 47 carried by the key break lever D² is so positioned that the free end thereof will cooperate with the pin 45 in a manner analogous to that of the cooperation of the pin C⁵ and arm D⁴ of the aforesaid Johnson patent.

A controlling dog 51 is pivotally mounted at 53 near the free end of the arm 41. A spring 55 is so applied to said dog as to tend to swing it around its pivot 53 in a clockwise direction.

A contact actuating extension bar 57 is carried by the dog 51 and extends past the pinion 23, so that said pinion forms a limit to the clockwise movement imparted to said dog by the spring 55.

A face 59 is carried by the dog 51 for abutting cooperation with the pinion 23. Said face is so formed that, when the armature C³ is in fully attracted or portative position, said face will be withdrawn a short distance from the pinion 23 (as indicated in Fig. 2), and such that movement of said armature responsive to retractile spring C⁴ will be arrested, by engagement of said face with the pinion 23, before said armature has moved out of the effective range of the magnet C (as indicated in Fig. 3).

An arm 61 relates with the shaft 21 for engaging a pin 63 carried by the dog 51. The form and relationship of said arm to said pin is such that said pin will be out of the path of said arm while the armature C³ is in attracted position and will be in the path of said arm when the face 59 is resting against the pinion 23, as indicated in Figs. 3 and 4. In the latter instance, said arm may engage said pin and thereby swing said dog 51 around its pivot 53 so as to disengage the face 59 from the pinion 23; whereupon limited movement of the armature C³ may be permitted responsive to the spring C⁴ (assisted by the action of the arm 61 upon the pin 63).

A stop 65 is disposed in the path of lengthwise movement of the bar 57 in the direction urged

5 by the force transmitted thereto from the spring C¹ acting through the lever C¹ and the arm 41. The positioning of said stop 65 is such that should the face 59 climb upon the pinion 23 to a height such as might otherwise permit said face to pass above and toward the right of said pinion (say 10 slightly beyond the position indicated by Fig. 4) said stop 65 will arrest such movement of the bar 57 before it has been carried to a position where the armature C³ is out of the effective range of the magnet C. The upper end of the stop 65 is so positioned that the bar 57 may, resultant from the action of the arm 61, pass above said stop and be there supported following disengagement of the arm 61 from the pin 63, as indicated 15 in Fig. 5.

20 An insulating pin 67 is carried by the bar 57 near the free end thereof. Contacts 69 are so positioned relative to bar 57 that when said bar is resting upon the upper end of the stop 65, said pin 67 will effect closed positioning of said contacts, as indicated in Fig. 5.

25 The relationship of the parts for actuation of the contacts 69 (as indicated in Figs. 1 to 5, inclusive), will be found suitable for transmitters having signal wheels with teeth formed in such portion of the periphery thereof that, when operating at intended timing between signal strokes, the time occupied by angular movement of the wheel E during which energization of the magnet C can prevent the parts from reaching the positioning indicated in Fig. 5 during the current 30 revolution of the wheel E will be longer than the longest time between closures of any signal.

35 If it is desired that the time required for the dog 51 to reach such positioning shall exceed that resultant from the use of parts such as those of Figs. 1 to 5, inclusive,—the alternative arrangement indicated in Fig. 10 (which will be herein- 40 after more fully described) should be substituted.

45 In any event, the parts should be of such form and relative arrangement that effective signal formulation in the ground path shall occur only after the expiration of a time, measured by the running of the train (as exemplified by the rotation of the shaft 21), which time exceeds the longest time which elapses between closures incident to any signal; and throughout which time 50 attained cumulative movement of the dog 51 (or any part utilized in place thereof) will be cancelled in the event of movement of the armature C³ to attracted position.

Furthermore, the relationship of the arm 61 and other parts which actuate the ground path controlling contacts should be such, with relation 55 to the emergency code wheel 25, that this path will be rendered effective only at a stage in the rotation of the emergency code wheel 25 such that the closure of the emergency contacts 33 next effected after closure of the emergency 60 path contact 69 will be that closure which precedes the first signal stroke, or the separation of the contacts 33, incident to the ensuing formulation of the intended code signal of the emergency wheel 25; and such that movement of the armature C³ out of the effective field of the magnet C (such as occurs when the bar 57 passes above the 65 stop 65) will occur only when the flange A² is so positioned with relation to the projection B¹ that said projection cannot fully enter the opening A³ immediately following full presentation 70 of said opening thereto.

75 A member 71 is pivotally supported by the shaft C² for movement independently of the armature lever C¹ and of the arm 41.

A pin 73 is carried by the member 71, near the free end thereof, and is arranged for cooperation with the arm D⁴ carried by the key break lever D² in a manner analogous to that of the pin C⁵ and of the arm D⁴ of the aforesaid Johnson 5 patent. The relationship between said pin 73 and said arm D⁴ to that between the pin 45 and the finger 47 is such that when the member 71 is so positioned that the pin 73 is in the path of the arm D⁴, said arm D⁴ will be supported in a 10 position high enough to carry the free end of the finger 47 slightly above the pin 45.

The extreme lower end C⁶ of the member 71 is so formed as to be suited for cooperation with the pin C⁷ carried by the gear C⁸ in a manner 15 corresponding to that of the similarly designated parts indicated in the aforesaid Johnson patent.

The stud 81 pivotally supports the non-interference latch 83 and the succession latch 85, for 20 movement independently one of the other.

A pin 87 is carried by the plate 89, which plate is secured to the arm 41. Said pin is so positioned that it will at all times support the upper end of said latch 83. A shoulder 91 is formed in the lower surface of said latch 83 in such location 25 that attracted positioning of the armature C³ will (through the lever C¹, arm 41, plate 89, pin 87, latch 83 and stud 81) cause positioning of the member 71 such that the pin 73 will be out of the path of the arm D⁴.

30 A stationary pin 93 is so situated with relation to an upturned lower end 97 of the latch 83 that, when the member 71 is permitted to swing counter-clockwise (incident to retraction of the armature C³ such as will carry the face 59 into engagement with the pinion 23) engagement of said pin 93 with said end 97 will cause shoulder 91 to be swung out of the path of the pin 87 and thereby permit member 71 to swing an additional distance in counter-clockwise direction and hence 40 to carry said shoulder to the right of the pin 87 where it cannot be reengaged by said pin upon movement of the armature to attracted position. With such conditioning of parts, the pin 87 may move in a clockwise direction pursuant to attracted 45 movement of armature C³, without thereby affecting the positioning of the member 71.

The succession latch 85 carries a projection 101 for limiting the clockwise rotation of said latch around the stud 81. Said latch 85 projects below said stud 81 into the path of a bar 103 50 which is carried by the arm 41 for a purpose hereinafter more fully explained.

A pin 105 is carried by the latch 85 for cooperation with the free end of the detent arm B in a manner analogous to that of the cooperation 55 of the pin C⁹ with the arm B of the aforesaid Johnson patent. The positioning of said pin 105 is such that when the latch 85 is so situated on its stud 81 as to bring the projection 101 to rest against the edge of said member 71, positioning 60 of said member 71 such as will withdraw the pin 73 from the path of the arm D⁴ will also cause said pin 105 to be withdrawn from the path of the shoulder 107 formed in the end of the detent arm B; and positioning of said member 71 such as 65 will allow the pin 73 to lie in the path of the arm D⁴ and bring about disengagement of the non-interference latch 83 from the pin 87, will also result in the positioning of said pin 105 in the 70 path of said shoulder 107.

The spring 109 is so applied to the latch 85 as to urge clockwise movement of said latch about the stud 81. Furthermore, spring 109 is so applied that after the latch 85 has so moved around 75

Its pivot 81 as to bring the projection 101 into engagement with the edge of the member 71, said spring will act through said latch to urge movement of said member 71 in counter-clockwise direction.

Said spring is further so applied to said latch 85 that it may, at times, act therethrough for causing said member 71 to swing in a clockwise direction. Thus when, in the course of downward movement of the detent arm B, the slanting surface thereof situated below the shoulder 107 acts upon said pin 105 (as will be best understood by reference to Figure 1 of the aforesaid Johnson patent), said spring 109 will cause said latch 85 to rock around said pin 105 thereby swinging member 71 clockwise for sufficient distance to carry the end C⁶ thereof into the path of the pin C⁷ moving with gear C⁸. At or about this time, pin C⁷ will engage the end C⁶ and effect further clockwise movement of member 71 sufficient to move the pin 73 out of the path of the free end of the arm D⁴ and to enable the pin 87 to be reengaged by the shoulder 91. Thus the member 71 will be retained in its normal position if 25 and for as long as the armature C³ is in its attracted position.

The relationship between the portion of the latch 85 extending below the stud 81 to the bar 103 is such that when the armature C³ is in its 30 fully retracted position, (thus carrying the free end of the arm 41 to the position indicated by Fig. 5) the bar 103 will engage the lower end of said latch 85 and swing same counter-clockwise around the stud 81 carrying the pin 105 out of the path of the shoulder 107 formed in the free 35 end of the detent arm B.

A bar 111 is carried near the free end of the detent arm B, for cooperation with the slanting surfaces 113 and 115 of the plate 89 and of the 40 member 71, respectively.

The slanting surfaces 113, 115 are so formed that, when the projection B¹ is supported by the flange A² and hence the detent arm is in its elevated position, said bar 111 will permit maximum retractive movement of the armature C³ and maximum counter-clockwise rotation of the member 71.

Said surfaces 113, 115 are further so formed that when the detent arm B is in its normal or 50 lower position (the projection B¹ having fully entered the opening A³), said bar 111 will assure fully attracted positioning of the armature and the member 71 will be in its extreme clockwise 55 positioning where the shoulder 91 of latch 83 will be permitted to engage pin 87. Such engagement prevents positioning of the member 71 such as would carry the pin 73 into the path of the arm D⁴, other than incidental to retraction of the armature with subsequent unlatching 60 of shoulder 91 from pin 87, as already hereinbefore described.

The surfaces 113, 115 are still further so formed that when the detent arm B is at the elevation which it occupies when the shoulder 107 is resting upon the pin 105 (the projection B¹ having 65 partially entered the opening A³), said bar 111 will cause positioning of the armature within the effective field of attraction of the magnet C and such positioning of the member 71 that the end C⁶ thereof will be situated in the path of the pin C⁷.

The emergency signal or code wheel 25 is fixed upon the shaft 21 for rotation with the code wheel E. The code wheels 25 and E may be arranged 75 for effecting the formulation of the same or of

different code signals. If desired, the emergency wheel 25 may be formed for transmitting code signal of the wheel E with the addition of a prefix or a suffix indicative of the fact that the signal is being transmitted upon an emergency basis.

For reasons well understood by those skilled in this art, it is desirable that these signal wheels be of the so-called "open type" (i. e., making all closures of like duration while breaks are of various durations) in order to facilitate the attainment of so-called "perfect non-interference" between a plurality of such boxes when associated with a single series circuit.

The key break lever 31 is moved responsive to the contour of the wheel 25, and is operable thereby independently of the lever D², for effecting actuation of the emergency code signal formulating contacts 33.

A protective shunt is diagrammatically indicated at 119, for normally short-circuiting the current path through the signaling contacts D and the windings of the magnet C, in accordance with general practice in the fire alarm art. An example of protective shunting mechanism suitable for accomplishing this purpose is shown in applicant's prior Patent No. 1,999,859. Said current path (which will also be referred to as the "normal current path") comprises the conductors 121, 123 and 125 together with said contacts D and magnet windings.

An emergency current path is provided, serially including the contacts 33 and 69 between the earth ground and the normal current path; said emergency path also comprising the conductors 131, 133 and 135.

In order to facilitate description of the operation of the signal transmitter of Fig. 1, there is shown, in association therewith, a source of current and signal manifesting or responsive instruments arranged in accordance with applicant's prior Patent No. 2,018,656, dated October 29, 1935, to which reference is had. Such arrangement will be briefly herein described as follows:

A bridge rectifier 141 has alternating current supply conductors 143, 145 applied to the input terminals thereof, and has conductors 147, 149 connected to the output terminals thereof, which latter conductors lead to the respective terminals of the protective shunt 119 and serially include 50 the manifesting devices 151 and 153 respectively, as well as any other signal transmitters which may be included in the circuit.

A ground connection G is established with input conductor 143, which ground connection 55 serially includes the input terminals of the bridge rectifier 155; an emergency responsive instrument 157 being connected to the output terminals of said rectifier.

Normal positioning of parts

Under normal conditions, the train is held at rest through engagement of a wall of the flange A² with the projection B¹. The bar 111 retains the armature in attracted position and holds the member 71 in its extreme clockwise positioning. The key break lever D² is held in elevated position by engagement of the pin A⁴ with the end A⁵, and contacts D are therefore held closed. The lever 31 rests upon a cut-away portion of the emergency code wheel 25, so that the contacts 33 are open.

The bar 51 rests upon the pinion 23, therefore the ground path controlling contacts 69 are open. The protective shunt 119 is closed, so that cur- 75

rent flow through the normal circuit path, between the terminals of the rectifier 141, passes serially through conductor 147 including manifesting device 151, through protective shunt 119, and through conductor 149 including manifesting device 153. Manifesting device 157 is de-energized.

Operation, clear circuit

- 10 If the detent arm is lifted at a time when the normal circuit path is in its normal closed condition (the protective shunt being then broken, in accordance with conventional practice) the current flow from one to the other of the output terminals of the rectifier 141 will 15 pass serially through conductor 147 including manifesting device 151, through conductor 125, contacts D, conductor 123, windings of electromagnet C, conductor 121, and conductor 149 including manifesting device 153.
- 20 Interruption of the current path through the shunt 119 occurs before the bar 111 has been lifted far enough to permit significant movement of the armature away from the magnet. Such interruption will cause effective energization of 25 the non-interference magnet C, which magnet will thereupon act to retain the armature C³ in attracted position, notwithstanding ensuing withdrawal of the bar 111 from supporting relation to the plate 89.

30 Withdrawal of the projection B¹ from the path of the flange A² will permit operation of the gear train, carrying said flange under said projection and causing rotation of the shaft 21 and parts moving therewith. The bar 111 will 35 be thus raised to a position permitting full retraction of the armature and maximum counter-clockwise rotation of the member 71.

35 The pin A⁴ will thereafter be moved along the upper surface of the end A⁵ of the key break lever 40 D² until the first tooth of the signal wheel E is in position to support said lever, when said pin A⁴ will pass out of the path of said end A⁵.

40 Further rotation of the code wheel E will then withdraw the first tooth thereof from support 45 of the key break lever D², whereupon said lever will fall responsive to the tension of the lower one of the contacts D, aided by gravity, thereby breaking the normal circuit path and causing response of the manifesting devices 151 and 153.

45 Such interruption of the normal circuit path also causes deenergization of the non-interference magnet C. However, the downward movement of the key break lever D² preceding and 50 incidental to such deenergization of said magnet carries the finger 47 into the path of the pin 45, thereby mechanically holding the armature C³ against retractive movement responsive to the retractile spring C⁴.

55 Ensuing rotation of the code wheel E will cause the next tooth to move lever D² upwardly, in the course of which movement the contacts D are re-closed, thereby causing reenergization of the non-interference magnet C. Further upward movement of lever D² will carry the finger 47 out of the path of the pin 45. However, armature C³ will remain in attracted position, due to the energization of the magnet C.

60 Still further rotation of the code wheel E will 65 permit downward movement of the key break lever D² with attendant opening of contacts D and deenergization of magnet C. Throughout the period of operation under normal circuit conditions during which the finger 47 is withdrawn 70 from the path of the pin 45, contacts D are in

closed relationship and the magnet C is effective for retaining the armature C³ in attracted position.

75 The various parts will thereafter act in a manner corresponding to the foregoing description, the teeth and notches of the code wheel alternately causing closure and breaking of the normal current path so as to cause response of the manifesting devices 151 and 153 in a manner representative of the intended code signal, and incidentally accomplishing energizations and de-energizations of the magnet C and the retention of armature C³ against retractive movement either magnetically or mechanically, as just described.

10 After the intended number of revolutions of the shaft 21, the same or another notch A³ will be presented to the projection B¹, and the same or another pin A⁴ will engage the end A⁵, thus 15 causing restoration of the various parts to their normal positions.

20 Throughout the operation of the signal transmitter, as just described, the contacts 69 will have remained open; the pin 63 having been continuously held out of the path of the arm 61 so 25 that said arm could not raise the bar 57 to close the contacts 69.

25 Because of such continued open circuit conditioning of the contacts 69, no connection was 30 established between the earth at g and the normal current path, notwithstanding that the contacts 33 were subjected to functional actuation during each revolution of the shaft 21.

Operation on busy circuit

35 If the detent arm is lifted at a time when a signal of some other transmitter is in process of formulation in the normal circuit path, deenergization of the non-interference magnet C will occur while the key break lever D² is being supported by engagement of the pin A⁴ with the end A⁵, for reasons well understood by those skilled in this art.

40 Upon such deenergization of the magnet C, the armature C³ will be moved away from the magnet 45 by the retractile spring C⁴ until its movement is arrested by the face 59 of the dog 51 being brought to rest against the pinion 23, for the reason that the finger 47 will, upon the occasion of such deenergization, be maintained above the 50 path of the pin 45 because of the engagement between the pin A⁴ and the end A⁵ just referred to.

45 Such retraction of the armature C³ will withdraw the pin 87 from the position where it prevents counter-clockwise movement of the member 71 through blocking the path of the shoulder 91. Said member 71 will thereupon move in counter-clockwise direction, responsive to the urge of spring 109, thereby carrying the pin 73 into the path of the arm D⁴, so as to lock the key 60 break lever D² in its elevated or closed circuit position.

55 Incidental to such movement of the member 71, the end 97 of the non-interference latch 83 will be so moved relative to the pin 93 as to cause 65 the shoulder 91 to be withdrawn from the path of the pin 87, thereby permitting completion of the full intended counter-clockwise movement of the member 71.

60 While member 71 is in its extreme counter-clockwise position, no actuation of the armature C³ will bring pin 87 into engagement with said shoulder 91.

65 Throughout the ensuing formulation of the signal of the other active transmitter in the normal 75

circuit path, the non-interference magnet C will be energized incident to each closure of such signal and will thus cause the armature C³ to move to attracted position and thereby withdraw the face 59 from the pinion 23 as well as the pin 63 from the path of the arm 61.

Inasmuch as the angular movement of the arm 61 during its engagement with the pin 63 prior to its having carried said pin to the position shown in Fig. 5, occupies a time measured by the running of the train which exceeds the time between closures incident to any signal, as hereinbefore more fully explained,—it is evident that, during the running of the train while said arm 15 and said pin are in engagement, some closure incident to the signal of the other active transmitter will cause energization of the magnet C. Upon such energization, the armature C³ will move to attracted position. The pin 63 will 20 thereby be withdrawn from the path of the arm 61 and thus prevent further actuation of the dog 51 by said arm until said arm, having moved for nearly a complete revolution, again reaches the position where it may engage said pin 63.

25. Throughout the ensuing operation of the gear train under conditions as just described, the armature will be kept in the effective range of the magnet C, the key break lever D² will be locked against functional actuation, and the emergency path closing contacts 69 will remain open.

After a desired number of revolutions of the shaft 21, the same or another notch A³ of the detent flange will be presented to the projection B¹, thus permitting the detent arm B to move 30 downwardly until the shoulder 107 at the free end thereof rests upon the pin 105.

Incident to such downward movement of said detent arm, the face thereof below the shoulder 107 will act against the pin 105 (due to the formation thereof as more fully disclosed in the aforementioned Johnson patent) and thereby effect movement of the member 71 in clockwise direction, such as will move the end C⁶ into the path of the pin C⁷ carried by the gear C⁸. Continued rotation of the shaft 21 will then carry the pin C⁷ into engagement with the end C⁶ of member 71 and thus impart further clockwise movement to the member 71, withdrawing the pin 73 from the path of the arm D⁴.

50. Just prior to such withdrawal of the pin 73 from the path of the arm D⁴, the pin A⁴ will have engaged the end A⁵, thus lifting the arm D⁴ carried by the lever D² slightly above the path of the pin 73. Such freeing of the pin 73 from the arm D⁴ will facilitate movement of the member 71, besides assuring that said arm D⁴ will be prevented from moving from its closed to its open circuit position at the time when the pin 73 is withdrawn from the path thereof.

60. Thereafter, so long as the pin A⁴ maintains the arm D² in its fully lifted position, the pin 73 will be free to move into the path of the arm D⁴.

65. From the foregoing it will be evident that, while the arm D⁴ is supported either by the pin A⁴ or by the first tooth of the code wheel E, should the non-interference magnet become deenergized due to the formulation of the signal of some other transmitter, retraction of the armature C³ will result in the pin 73 being again carried into the path of the arm D⁴, and the mechanism will thereafter operate without effective formulation until an occasion is reached when the normal current path is free to respond to formulation of the

signal of this transmitter at a time when a notch A³ is adjacent to the projection B¹.

After the signal of the other transmitter has been completed and the circuit remains restored in its normal closed condition, the various parts 5 will act to cause signal formulation by the contacts D, after which the parts will be brought to rest, all as hereinbefore more fully explained.

Simultaneously started signals

10

If two transmitters are started in such timed relationship that their respective normal code signal formulating contacts D act simultaneously in breaking the circuit for their signals, a stage will be thereafter reached in the operation of such transmitters when, at one of said transmitters, the finger 47 will be lifted above the pin 45 at a time when the contacts D of the other transmitter are open. Thereupon, the armature C³ of such first named transmitter will be moved away from its associated magnet C by the retractile spring C⁴, and the ensuing operation of such first named transmitter will be analogous to that of a transmitter operating on a busy circuit, as hereinbefore more fully explained.

Operation, broken line

15

If the detent arm B is lifted at a time when the normal circuit is broken at one side or the other of the active transmitter, operation will at first proceed as in the event of operation on a busy circuit. However, inasmuch as no energizations of the magnet C will occur, the face 59 will not be withdrawn from the pinion 23, and the bar 57 will ultimately be moved into engagement with the stop 65 and thereafter lifted (through engagement of the pin 63 by the arm 61) until the pin 67 closes the contacts 69 and the end of the bar 57 rests upon the stop 65.

30. As hereinbefore more fully explained, such closure of the contacts 69 will occur at a time when the contacts 33 are open due to cut-away portion of the wheel 25 which precedes the first tooth of said wheel representative of the code signal being then presented to the lever 31.

35. Thereafter, the lever 31 will follow the contour of the wheel 25, thus effecting closures of the contacts 33 representative of the intended code signal.

Assuming that conductor 149 is broken and that the current path through conductor 147 is 40 effective, each such closure of the contacts 33 will establish a current path for causing functional actuation of the manifesting devices 151 and 157 as follows:

45. From one output terminal of rectifier 141, through conductor 147 and manifesting device 151, to and through conductor 125, closed contacts D, through a portion of conductor 123, through conductor 135, contacts 69, conductor 133, contacts 33 and conductor 131 to ground g; 50 thence through the earth to and through ground connection G to the input terminal of rectifier 141 which is associated with input conductor 143, thereby causing energization of manifesting device 157.

55. Correspondingly, if conductor 147 is broken and conductor 149 is effective, each closure of contacts 33 will establish a current path from the other output terminal of rectifier 141, through conductor 149 including manifesting device 153, through conductor 121, windings of magnet C, a portion of conductor 123, through conductor 135, contacts 69, conductor 133, contacts 33, and conductor 131 to ground g; thence 60 through the earth and through ground connection G to the input terminal of rectifier 141 which is associated with input conductor 143, thereby causing energization of manifesting device 157.

tion G to input terminal of rectifier 141 associated with input conductor 143, thereby effecting functional energization of manifesting devices 153 and 157, as well as causing energization of magnet C.

From the foregoing, it will be evident that the code signal of wheel 25 will be manifested by the device 157, irrespective of whether conductor 147 or 149 is broken; and that the one of the manifesting devices 151, 153 which is associated with the unbroken conductor will also respond to such code signal.

Inasmuch as the armature C³ moved out of the effective field of the magnet C when the bar 57 was positioned on the stop 65 so as to close the contacts 69, any energizations of the magnet C which may occur incidental to closures of the contacts 33 will be without significant effect upon said armature.

Upon full retraction of the armature C³, incident to the positioning of the bar 57 as just referred to, the bar 103 engaged the lower end of the latch 85 swinging same around the stud 81 so as to withdraw the pin 105 from the path of the shoulder 107 formed in the end of the detent arm B. Consequently, when opening A³ is next presented to the projection B¹, the detent arm B will be permitted to fall, thereby stopping the operation of the transmitter and restoring all parts to their normal positions.

It will be noted that, inasmuch as the contacts 69 remained open during the first revolution of the wheel 25, the code number of said wheel will be transmitted a lesser number of times under broken line condition than would have been the case under normal line condition. For example, if operation under normal line condition would result in transmission of the signal of the normal wheel E four times, transmission of the signal of the emergency wheel 25 under circumstances here under consideration would be effective three times.

Operation, clear circuit becoming broken

If the circuit becomes broken, after this transmitter has started the formulation of its code signal therein, the resultant operation of the various parts will, when the circuit becomes broken, be analogous to that occurring in the instance of the one of simultaneously started transmitters which fails to retain control of the circuit; and will thereafter continue in a manner analogous to that under broken line operation.

If the break occurs during the first transmission or "round" of the code signal, or at a time thereafter and preceding an ensuing round such that the contacts 69 would become closed prior to the commencement of such ensuing round, the contacts 33 will be effective for formulating the signal in the emergency ground path during the ensuing round or rounds.

If, however, the break does not become effective early enough to cause the contacts 69 to become closed before the commencement of the last round, the opening A³ in the flange A² will permit the detent arm B to move the armature C³ so as to withdraw the pin 63 from the path of the arm 61, before said arm will have carried the dog 51 to a position where the bar 57 can pass over the top of the stop 65. Hence the pin 105 will be disposed in the path of the shoulder 107 and thereby prevent the train being brought to rest after the conclusion of the final intended revolution of the code wheels, and the train will continue thereafter to operate until the code signal has been formulated in the emergency ground

path a number of times which is one less than the number of intended formulations of the code signal in the normal circuit path.

Operation, busy circuit becoming broken

If, after having commenced operation on a previously busy circuit, that circuit becomes broken, the operation will be similar to that occurring when the circuit becomes broken while the transmitter is acting to formulate its signal 10 in a previously clear line.

In other words, the arm 61 will engage the pin 63 upon first opportunity after the circuit becomes broken, and will thereupon effect closure of the contacts 69 to render the contacts 33 15 effective for signal formulation in the emergency path, unless it so happens that an opening A³ is then presented to the projection B¹. In the latter event, the lowering of the detent arm B will temporarily prevent effective actuation of the dog 51 20 by the arm 61, for the reason more fully described in connection with "Operation, clear circuit becoming broken."

Operation on grounded line

The operation, when the normal circuit is closed and grounded at one side or the other of an active transmitter, is the same as that hereinbefore described for operation on a clear circuit; except that manifesting device 157 and one 30 or the other of the manifesting devices 151, 153 will fail to respond to the signal.

For example, if conductor 147 is grounded, operation of the transmitter of Fig. 1 will cause response of manifesting device 153 but manifesting devices 151 and 157 will not respond to the signal. Correspondingly, if conductor 149 is grounded, operation of the transmitter will cause response of manifesting device 151 only.

Operation, short-circuited magnet

If, at a time when the detent arm is lifted, the windings of magnet C are short-circuited as by so-called "burning" out of the windings or by a short-circuit between conductors 121 and 123, 45 or otherwise, the operation of the transmitter will be identical with that hereinbefore described under heading of "Operation, broken line", except that the manifesting devices 151 and 153 will be unresponsive to the resultant signal, which 50 will be shown only by manifesting device 157.

Operation, shunted-out transmitter

The operation of the transmitter of Fig. 1, when shunted out, is identical with that hereinbefore described under heading of "Operation, broken line", the manifestation of the signal thus formulated being the same as that hereinbefore more fully described under heading of "Operation, short-circuited magnet".

Operation, broken magnet winding

In the event of a break in conductor 121, in conductor 123, or in the windings of non-interference magnet C, operation of the transmitter of Fig. 1 would result in operation such as that hereinbefore described in greater detail under "Operation, broken line" with reference to a break in conductor 149.

If, however, at a time when the transmitter of Fig. 1 was attempting to transmit its code signal, the conductor 147 was broken, in addition to a break in the current path through the windings of the non-interference magnet C, there would be no current path available for carrying

the formulated signal from the transmitter to the manifesting devices 151, 153 or 157.

Fig. 6 embodiment

5 The embodiment of this invention indicated in Fig. 6 contemplates the utilization of contacts 169 of Fig. 6 in place of the emergency path controlling contacts 69 of Figs. 1 to 5, inclusive. Such contacts 169 are arranged in association with a pin 171 carried by the armature lever C¹. Pin 171 is in such relationship to the contacts 169 that they will be in open circuit condition during attracted positioning of the armature C¹ as well as during retracted positioning of the armature such as will bring the face 59 of bar 57 into engagement with the pinion 23.

10 The bent-over end 173 of one of the contacts 169 is of such form and positioning, relative to the path of the pin 171, that the pin 171 will engage said end 173 and effect closed circuit positioning of the contacts 169 when the armature lever C¹ is fully retracted, that is, in the position which it occupies when the bar 57 is resting upon the upper end of the stop 65 as indicated in Fig. 5.

15 The contacts 169 are serially connected between conductors 133 and 135 in substitution of contacts 69 of Figs. 1 to 5. A transmitter constructed in accordance with the aspect of this invention indicated by Fig. 6 will operate, under 20 all conditions, in a manner analogous to that hereinbefore more specifically described.

Fig. 7 embodiment

25 In Fig. 7 there is shown an arrangement of parts, pursuant to this invention, such that signal formulation will be effected between the ground and the portions of the normal circuit situated at both sides of an active transmitter, even if the current path through the non-interference 30 magnet winding of such transmitter is interrupted.

35 This result is accomplished by the utilization of contacts 181, 183 and 185 in substitution for the contacts 69 indicated in Figs. 1 to 5 in association 40 with the pin 67 carried by the bar 57 or in substitution for contacts 169 associated with the pin 171 in accordance with Fig. 6. These contacts 181, 183, 185 are arranged to be closed together only under conditions such as would cause closure 45 of the contacts 69 or 169.

50 Contact 181 is connected with one of the contacts 33 by conductor 233. Contact 183 is connected to conductor 225 through conductor 235, and contact 185 is connected to conductor 221 through conductor 187; conductors 221 and 225 respectively corresponding to conductors 121 and 125 indicated in Fig. 1.

55 From the foregoing it will be evident that, in the use of an embodiment of this invention having the characteristics indicated by Fig. 7, if the current path through the windings of the electromagnet C is interrupted, and there is a break in the normal current path between the active transmitter and the central office manifesting 60 devices, the code signal of such active transmitter will cause response of the manifesting device 157, as well as one of the other of the manifesting devices 151, 153, irrespective of the one of the conductors 147, 149 which is broken, and irrespective of which of these conductors happens to be directly connected with conductor 221 of the active transmitter.

70 The reason for this result is that, pursuant to the arrangement indicated in Fig. 7, emergency current paths are provided from both sides of the

75 normal current path to the ground when the emergency path contacts 181, 183, 185 are closed. For example, assuming that conductors 221 and 225 of Fig. 7 are connected to the protective shunt of Fig. 1 in the place of conductors 121 and 125 there shown, it is evident that, notwithstanding any break in the current path through the windings of the electromagnet, code signal formulation at contacts 33 will be effective through contacts 181, 183 and 185. With such an arrangement a current path is established from conductor 147 of Fig. 1, through conductors 225 and 235 of Fig. 7 to contact 183, and thence through contact 181, conductor 233, code contacts 33 and conductor 221 to the earth through ground connection g; and an alternative path is established from conductor 149 of Fig. 1, through conductors 221 and 187 of Fig. 7, thence through contacts 185 and 181, conductor 233, code contacts 33 and conductor 221 to ground connection g and the earth.

Fig. 8 embodiment

80 The circuit arrangement indicated in Fig. 8 discloses a manner in which this invention may be applied to transmitters having the normal code signal formulating contacts serially connected between one and the other of the windings of a non-interference magnet, such as the magnet C.

85 In accordance with the circuit arrangement indicated in Fig. 8, the conductors 321 and 325 correspond generally with the conductors 121 and 125 of Fig. 1, these conductors leading from the respective transmitter terminals or respective terminals of the protective shunt (such as the shunt 119 of Fig. 1) to terminals of one and the other of the windings of the non-interference magnet, so connected that when the remaining terminals of such windings are connected together by closure of the normal code signal formulating contacts, current flow between conductors 321 and 325 will cause cooperative excitation of these windings.

90 Such interconnection of the remaining terminals of the non-interference magnet windings are indicated in Fig. 8 wherein they are shown connected to the respective ones of contacts D⁸, which correspond to the normal code signaling contacts D of Fig. 1.

95 The conductor 335 connects one of the contacts D⁸ to one of the emergency ground path controlling contacts 69. The other of the contacts 69 is connected through conductor 333 to one of the emergency code signal formulating contacts 33. The other of the contacts 33 is connected through conductor 331 to the earth through ground connection g.

100 The operation of the embodiment of this invention indicated in Fig. 8 is substantially identical with that of the embodiment indicated in Fig. 1 as hereinbefore more fully described.

Fig. 9 embodiment

105 If desired, the emergency ground path controlling contacts 69 of Figs. 1 to 5, inclusive, and the contacts 169 of Fig. 6 may be omitted; the emergency code signal formulating contacts being mechanically governed in a manner such as will give results substantially identical with those 110 electrically obtained through the use of the contacts 33.

115 In accordance with Fig. 9, means for accomplishing such mechanical control of the emergency code contacts is indicated by a latch piece 75

191 pivotally supported at 193 and having a ledge 195 formed near the lower end thereof for engaging the free end 197 of the emergency key break lever 431.

5 A spring 199 urges movement of the piece 191 such as will carry the ledge 195 into the path of the end 197.

The arm 441 corresponds with the arm 41 of Fig. 1 and carries an extension 201 for engaging the piece 191 near its uppermost end and thereby swinging the ledge 195 out of the path of the end 197 whenever the arm 441 is in the position which it occupies when its associated dog 51 is resting upon the stop 65 as indicated in Fig. 5.

15 The emergency signal wheel 425 here shown is of a type which supports the lever 431 in elevated position except when signal formulating notches are presented thereto.

From the foregoing it will be evident that the 20 emergency code signal formulating contacts 433 will be held in open circuit position at all times except when the free end of the dog 51 is supported upon the stop 65; and that, at such times, the emergency key break lever 431 will follow the 25 contour of the code wheel 425, causing closures of said contacts whenever a notch in said contour is presented to said lever.

It should be understood that the construction indicated in Fig. 9 is merely diagrammatic and 30 that in the interests of clearness no attempt is here made to indicate means for causing quick action or so-called "snap action" in the separating movement of said contacts. Where rapidly moving code wheels are utilized, such supplemental equipment may be unnecessary. For instances in which such equipment may be deemed 35 needful, mechanism may be utilized for accomplishing this function in accordance with Patent No. 1,884,735 to George E. King, dated October 25, 1932, to which reference is made.

Fig. 10 embodiment

For situations where it is desired that closure 45 of emergency path contacts (such as the contacts 69 of Fig. 1) shall be accomplished only when actuation of the dog 51, or such part as may be used in place thereof, has not been interrupted, (as because of energization of the electromagnet) for a time represented by rotation of the shaft 21 through an angle greater than that obtainable through structure such as is indicated 50 in Figs. 1 to 5, inclusive,—modified parts may be used whereby any desired extent of rotation of the shaft 21 will have to take place during continuous deenergization of the electromagnet, before the emergency code signal formulating contacts will be rendered effective.

Such an arrangement is indicated in Fig. 10, 55 in which the pivot 553 corresponds with the pivot 53 of the preceding views. The dog 551 is pivotally mounted on the pivot 553 and has a toothed face 59' for engaging the pinion 23 under circumstances such as those which cause the face 59 of the dog 51 to engage the pinion 23 of preceding views.

The bar 557 moves with the dog 551 and is so formed with relation to a stop 565 that when the dog 551 has been swung counter-clockwise around pivot 553 through engagement of the toothed 60 face 59' with pinion 23, until the lower end of the face 59' is permitted to pass above pinion 23, during the ensuing movement of the pivot 553 incident to retractive movement of the armature C³, the end of the bar 557 will be brought against 65 the stop 565, and will there remain until the arm 70

61 engages the pin 63 and carries the free end of the bar 557 above the stop 565; to be there supported and thus cause the pin 567 to effect continuing closure of the emergency ground path controlling contacts 69.

From the foregoing it will be evident that the length of the toothed face 59' can be such as to be representative of any desired extent of rotational movement of the pinion 23 and that, throughout engagement of such face with said pinion incident to deenergization of the non-interference magnet, should re-energization of such magnet occur, the face 59' will be withdrawn from engagement with the pinion 23, and the dog 551 will fall to its starting position, and thus cancel any previously attained accumulative lifting of the dog 551.

Fig. 11 embodiment

As an example of one of the many alternative 20 embodiments of this invention, which may be made to conform with various operating conditions as well as for meeting differing preferences of users, an arrangement is shown in Fig. 11 in which all code signal formulating contacts are at 25 all times fully subject to actuation responsive to rotation of a single code wheel. Means is also provided whereby these contacts may be rendered ineffective for interrupting the normal current 30 path responsive to the formulation of the code signal by some other transmitter, and whereby, after continuing deenergization of the electromagnet for a time longer than the longest open circuit period incident to the transmission of 35 any code signal, these contacts may be caused to effect the formulation of the intended code signal between the normal path and the earth.

Referring now in greater detail to the arrangement indicated in Fig. 11, the normal code signal formulating contacts 721 are connected 40 through the conductors 723 and 725 with the respective ones of the noninterference shunting contacts 727. One of the noninterference shunting contacts 727 is connected through conductor 729 with one end of the non-interference electromagnet windings 781, the other end of these windings is connected to the conductor 783. The remaining one of the contacts 727 is connected with the conductor 785. The conductors 783 and 785 may be associated with the signaling circuit 50 in a manner analogous to that indicated in Fig. 1 for conductors 121 and 125.

The emergency code signal formulating contacts 733 correspond generally with the contacts 33 of Fig. 1 and, together with the contacts 721, are at all times subject to actuation of the key break lever 741 associated with the normal code wheel E, so that, when said lever 741 is lifted by any tooth of the wheel E, the contacts 721 and 733 will be closed; and when said lever 741 is allowed to fall due to presentation of a space between teeth of the wheel E, the contacts 721, 733 will be open. Furthermore, the lever 741 is subject to actuation, as by the pin A⁴ of Fig. 1, for lifting said lever and closing the contacts 721 and 733 when the transmitter is at rest, and just prior to and following the presentation of any opening A³ to the projection B¹.

The contacts 69 correspond with the contacts 69 of preceding views for like operation.

A finger 747 is pivotally mounted adjacent to and for movement independently of the lever 741, a pin 749 carried by the lever 741 projecting into the path of the finger 747 so that, when the lever 741 has been lifted by any tooth of the wheel E, 75

the free end of the finger 747 will be above the path of movement of the pin 45 carried by the bar 43 moving with the armature controlled arm 41 (see Fig. 1).

- 5 An insulating pin 775 moves with the member 71 and is so associated with the contacts 727 that, when said member 71 is in the position which it occupies when the armature is in attracted position and the pin 87 rests against the shoulder 91, said contacts 727 will be open; and when said member 71 has moved to the position which it attains after retraction of the non-interference armature, said contacts will be closed.

From the foregoing, it will be apparent that the operation of an embodiment of this invention, such as is indicated in Fig. 11, will be similar, under the various conditions, to that of a transmitter constructed in accordance with Fig. 1; except that both the contacts 721 and 733 will be concurrently actuated throughout all rotations of the wheel E; but the actuation of the contacts 721 may be rendered ineffective responsive to interference conditions, due to closure of the shunting contacts 727; and the contacts 733 will be rendered effective only during closure of the contacts 69.

Inasmuch as it is thus made evident that the signal formulating means may be variously embodied, the phrase "signal formulator" will be hereinafter used as designating formulating contacts such as the contacts D in association with the key break lever D² and wheel E, correspondingly employed contacts 33, lever 31 and wheel 25 of Fig. 1; corresponding formulating contacts, key break levers and signal wheels of Figs. 7, 8 and 9; and either the contacts 721 or 733 with lever 741 and wheel E of Fig. 11, or both the contacts 721 and 733 of said Fig. 11 in such instances as the context permits or requires.

40 It will be evident, from the foregoing description, that this invention might be illustrated in the drawings of the present application as embodied in various ones of many other different kinds of mechanisms. Those mechanisms which have been selected for use as illustrative of the invention have been chosen not because they exhaust the scope of the invention in its application to the various uses for which it is suited; but they have been selected because they are believed to be such as will be most helpful in enabling those skilled in this art to successfully apply this invention to any use for which it is suited.

While there has been shown in the accompanying drawings, and hereinbefore described in considerable detail, certain specific embodiments of this invention,—it should be understood that such disclosure is in many instances illustrative only, and for the purposes of making clear the nature and objects of this invention; however, this invention is not limited to the particular arrangements shown and hereinbefore described, as many changes may be made in the construction and arrangement and parts may be added, changed or omitted, without departing from the spirit of this invention.

It is also to be understood that the language used in the following claims is intended to cover all of the generic and specific features of the invention herein described and all statements of the scope of the invention which, as a matter of language, might be said to fall therebetween.

I claim:

1. In a signal device operable for a series of formulating cycles,—means manually operable from a normal to a fully actuated position for

initiating operation of said device, means for maintaining said manually operable means in fully actuated position and for permitting restoration thereof after a predetermined number of such cycles, circuit controllers subject to concurrent code signal formulating actuation incident to each formulating cycle of the operation of said device, an electromagnet having a winding conductively associated with one of said controllers, a part movable to a first position in which it is retainable responsive to energization of said magnet, to a second position from which it is movable to said first position responsive to such energization, and to a third position where it is unaffected by such energization, means for effecting movement of said part from its second to its third position only following a predetermined extent of operation of said device throughout which said part has remained in its said second position and thereafter only at a predetermined operating cycle stage, said last named means comprising a member pivotally connected with said part for engagement with a moving member of said device to restrain movement of said part from its said second to its said third position, said member subject to actuation responsive to operation of said device to a position permitting movement of said part from its said second position to its said third position, a member alternatively positionable for rendering said associated one of said controllers effective and ineffective, means for effecting positioning of said member to render said one controller effective only while said part is in its first position, said last named means involving a non-interference latch pivotally connected with said second named member, engageable with a surface movable with said part and with a stationary surface whereby said second named member may be retained in effective positioning while said part is in its said first position and said non-interference latch will be moved out of the path of the part-associated-surface during ineffective positioning of said member, means for moving said member from the position rendering said controller ineffective to the position rendering it effective only at a predetermined stage of an operating cycle, means for rendering the other of said controllers effective only when said part is in the third of its said positions, means for preventing full restoration of said manually operable means to its normal position following operation of said device for the aforesaid predetermined series of formulating cycles, and means jointly controlled by said part and said second named member for rendering said restoration preventing means effective only when said second member is positioned for rendering said associated controller ineffective and said part is withdrawn from its aforesaid third position, said jointly controlled means comprising a succession latch pivotally associated with said second named member and carrying a surface which may be brought into the restoration path of said manually operable means, a spring urging movement of said latch to such obstructing position, and surfaces moving with said succession latch whereby said latch will be rendered obstructingly effective only when said part is in its said first or second position and said member is positioned for rendering said associated controller ineffective.

2. In a signal device operable for a series of formulating cycles,—means manually operable from a normal to a fully actuated position for

initiating operation of said device, means for maintaining said manually operable means in fully actuated position and for permitting restoration thereof after a predetermined number of such cycles, circuit controllers subject to concurrent code signals formulating actuation incident to each formulating cycle of the operation of said device, an electromagnet having a winding conductively associated with one of said controllers, a part movable to a first position in which it is retainable responsive to energization of said magnet, to a second position from which it is movable to said first position responsive to such energization, and to a third position where it is unaffected by such energization, means for effecting movement of said part from its second to its third position only following a predetermined extent of operation of said device throughout which said part has remained in its said second position and thereafter only at a predetermined operating cycle stage, a member alternatively positionable for rendering said associated one of said controllers effective and ineffective, means for effecting positioning of said member to render said one controller effective only while said part is in its first position, means for moving said member from the position rendering said controller ineffective to the position rendering it effective only at a predetermined stage of an operating cycle, means for rendering the other of said controllers effective only when said part is in the third of its said positions, means for preventing full restoration of said manually operable means to its normal position following operation of said device for the aforesaid predetermined series of formulating cycles, and means jointly controlled by said part and said member for rendering said restoration preventing means effective only when said member is positioned for rendering said associated controller ineffective and said part is withdrawn from its aforesaid third position.

3. A signal formulating transmitter comprising two individual signal formulating contact making and breaking devices, means whereby one of said devices is normally effective for signal formulation and the other is normally ineffective for signal formulation, means for at times concurrently operating said two signal formulating devices, a normal signal path through the transmitter including therein the normally effective signal formulating device, an auxiliary signaling path including therein in series the normally ineffective signal formulating device, the normally effective signal formulating device and portions of said normal path, a non-interference magnet in said first path, means controlled by the non-interference magnet when said operating means for the signal formulating means is operative for determining whether said first path is ineffective for signal formulation therein temporarily or for a period of time longer than the longest interval due to normal signal formulation, means controlled by the determining means in either event for rendering the normally effective formulating means ineffective to formulate signals in the first path or to affect the signaling in said second path, and additional means operated by the determining means only when it determines that the first path is ineffective for the longer time interval for rendering the second formulating device effective in the additional path.

4. A signal formulating transmitter comprising two individual signal formulating contact making and breaking devices, means whereby

one of said devices is normally effective for signal formulation and the other is normally ineffective for signal formulation, means for at times concurrently operating said two signal formulating devices, a normal signal path through the transmitter responsive to the normally effective signal formulating device, an auxiliary signaling path responsive to the normally ineffective signal formulating device and involving the normally effective signal formulating device and portions of said normal path, a non-interference magnet responsive to said first path, means controlled by the non-interference magnet when said operating means for the signal formulating means is operative for determining whether said first path is ineffective for signal formulation therein temporarily or for a period of time longer than the longest interval due to normal signal formulation, means controlled by the determining means in either event for rendering the normally effective formulating means ineffective to formulate signals in the first path or to affect the signaling in said second path, and additional means operated by the determining means only when it determines that the first path is ineffective for the longer time interval for rendering the second formulating device effective in the additional path.

5. A signal formulating transmitter comprising two individual signal formulating contact making and breaking devices, means whereby one of said devices is normally effective for signal formulation and the other is normally ineffective for signal formulation, means for at times concurrently operating said two signal formulating devices, a normal signal path through the transmitter including therein the normally effective signal formulating device, an auxiliary signaling path including therein the normally ineffective signal formulating device and involving portions of said normal path, a non-interference magnet responsive to said first path, means controlled by the non-interference magnet when said operating means for the signal formulating means is operative for determining whether said first path is ineffective for signal formulation therein temporarily or for a period of time longer than the longest interval due to normal signal formulation, means controlled by the determining means in either event for rendering the normally effective formulating means ineffective to formulate signals in the first path or to affect the signaling in said second path, and additional means operated by the determining means only when it determines that the first path is ineffective for the longer time interval for rendering the second formulating device effective in the additional path.

6. A signal formulating transmitter comprising two individual signal formulating contact making and breaking devices, means whereby one of said devices is normally effective for signal formulation and the other is normally ineffective for signal formulation, means for at times effecting concurrent cyclic operation of said two signal formulating devices, a normal signal path through the transmitter including therein the normally effective signal formulating device, an auxiliary signaling path including therein in series the normally ineffective signal formulating device, the normally effective signal formulating device and portions of said normal path, a non-interference magnet in said first path, means controlled by the non-interference magnet when said operating means for the signal formulating

- means is operative for determining whether said first path is ineffective for signal formulation therein temporarily or for a period of time longer than the longest interval due to normal signal formulation, means controlled by the determining means in either event for rendering the normally effective formulating means ineffective to formulate signals in the first path or to affect the signaling in said second path, additional means operated by the determining means only when it determines that the first path is ineffective for the longer time interval for rendering the second formulating device effective in the additional path, and means associated with the operating means whereby one and the other of the formulating devices will be rendered effective for commencement of signal formulation in their respectively associated paths only at predetermined cycle-stage of said operating means.
7. In a signal formulating transmitter,—a normal current path, an emergency current path for at times serving to supplement said normal path, contacts respectively associated with said paths for effecting signal formulation therein, means operable for severally effecting cyclical signal formulating activity of said contacts, an electromagnet responsively associated with said normal path, non-interference mechanism governed by said magnet responsive to impairments of current flow in said normal path, such as result from a busy or a broken line, for conditioning said mechanism for suspending signal formulation in said normal path by its associated contacts, means responsive to said mechanism for effecting signal formulation by its asso-

ciated contact in said emergency path only following non-portative conditioning of said magnet continued for a predetermined time measured by the operation of said operable means and only during conditioning of said mechanism for suspension of signal formulation in said normal path, and means for permitting commencement of signal formulation in one and the other of said paths only at predetermined cycle-stage in the operation of said operable means.

8. In a signal formulating transmitter,—a normal current path, an emergency current path for at times serving to supplement said normal path, contacts respectively associated with said paths for effecting signal formulation therein, means operable for severally effecting cyclical signal formulating activity of said contacts, an electromagnet responsively associated with said normal path, non-interference mechanism governed by said magnet responsive to impairments of current flow in said normal path, such as result from a busy or a broken line, for conditioning said mechanism for suspending signal formulation in said normal path by its associated contacts, means responsive to said mechanism for effecting signal formulation by its associated contact in said emergency path only following non-portative conditioning of said magnet continued for a predetermined time measured by the operation of said operable means, and means for permitting commencement of signal formulation in one and the other of said paths only at predetermined cycle-stage in the operation of said operable means.
